UNITED STATES PATENT OFFICE.

EDMUND JAMES LOWRY, OF SOUTH BEND, INDIANA, ASSIGNOR TO OLIVER CHILLED FLOW WORKS, OF SOUTH BEND, INDIANA.

ART OF MOLDING.

Application filed February 18, 1921. Serial No. 446,150.

To all whom it may concern:

Be it known that I, EDMUND J. LOWRY, a citizen of the United States, and a resident of South Bend, in the county of Saint Joseph and State of Indiana, have invented 5 certain new and useful Improvements in the Art of Molding; and I do hereby declare the following to be a full, clear, and exact description of the invention, such as 10 will enable others skilled in the art to which it appertains to make and use the same.

This invention relates to improvements 15 in the art of molding or casting and to improvements in permanent two-part molds and means for manipulating and controlling the operation of the same,—one object of the invention being to so construct a molding apparatus of the type specified that the speed of its operation in the making of 20 castings of a high degree of perfection shall be enhanced.

A further object is to so construct the molding apparatus as to avoid liability of 25 injury thereto during the casting or molding operations and which will also reduce to a minimum imperfections in the castings.

A further object is to provide means for 30 making plow points and shares having chilled edges so that the chilled portion of the edge shall be uniform, and so that a maximum degree of strength and hardness shall be obtained in the share or point, thus resulting in enhancing the longevity of the same.

With these and other objects in view, the 35 invention consists in certain novel features of construction and combinations of parts as hereinafter set forth and pointed out in the claims.

In the accompanying drawings; Figure 1 40 is a side elevation of a molding apparatus illustrating an embodiment of my invention and showing the mold members or dies closed; Figure 2 is a similar view showing 45 the mold members open or separated; Figure 3 is a plan view with the mold members in closed position; Figure 4 is an end view; Figure 5 is an enlarged fragmentary sectional view on the line 5—5 of Figure 3; 50 Figures 6, 7, 8 and 9 are views of the mold members, and Figure 10 is a view illustrat-

ing a portion of a plow share or point as molded in the apparatus.

1 represents a table or supporting frame on which the apparatus is mounted. Angu- 55 lar bars 2, 2 are secured upon the table and suitably spaced apart in parallel relation to each other to receive the members 3 and 4 of a permanent mold between them. The mold member 3 is loosely pivoted near its 60 bottom as at 6 to the angle bars 2, 2 and said mold member is rounded as at 5 so that it may turn or tilt on such pivotal connec- 65 tion. The angle bars 2 are notched to form inclined edges 7 and the mold member 3 is 70 provided on its side portions with shoulders 8 which may rest on the inclined edges 7 when the mold member is tilted and thus limit the tilting movement of said member and hold it in tilted position.

At one end of the table or frame 1, an abutment 9 is provided for the pivoted mold member 3 and from said abutment, arms 9^a project for guiding said mold member.

The mold member 4 is mounted to slide 75 on the table between the guide bars 2 and the table may be provided with an opening 10 through which the casting may be discharged.

The sliding mold member 4 is moved to- 80 ward and away from the mold member 3, by means of a motor located upon the frame or table 1. This motor comprises a cylinder 11 having a suitable piston therein, and the rod 12 of this piston is connected with a 85 cross head 13 secured to the mold member 4. A U-shaped pipe 14 is connected with ports at respective ends of the cylinder 11, and at a convenient point between the ends of this pipe, a valve 15 is located and con- 90 structed to direct compressed air (received from any suitable source of compressed air supply communicating with the casing of said valve) to one or the other end of the cylinder for causing movement of the mold 95 member 4 in one direction or the other. The operation of the valve 15 is controlled by the molder through the medium of foot- operated lever mechanism. This mech- 100 anism comprises a foot lever 16 pivotally sup- ported at 17, a rod 18 pivotally connected to one end of said lever, and an arm 19 se-

cured to the stem of the valve 15 and pivotally connected with the upper end of the rod 18. This lever mechanism is so proportioned that the weight of the forward end 5 of the lever 16, the rod 18 and arm 19 will predominate over the weight of the free arm of said lever and thus operate normally to hold the valve 15 in position to supply motive fluid to the inner end of the cylinder 10 and thus retain the mold member 4 withdrawn, as shown in Figure 2. In order to facilitate such operation, the pivotal connections between the parts constituting said lever mechanism are made loose. It is evident 15 that when the molder depresses the free end of the foot lever, the parts constituting the lever mechanism will be moved from the positions shown in Figure 2 to the positions shown in Figure 1; the valve 15 20 will be shifted and the motor will operate to move the mold member 4 to and against the mold member 3 as shown in Figure 1. It is equally evident that when the molder releases the foot lever, the parts of the lever 25 mechanism will at once assume the positions shown in Figure 2, shifting the valve 15 and effecting separation of the mold member 4 from the mold member 3 as shown in Figure 2, to release the casting and permit to escape 30 through the opening in the frame or table 1.

Motive fluid other than compressed air may be employed for operating the motor but I prefer to employ a compressible fluid as the same will act, not only to move the 35 mold member 4 relatively to the mold member 3, but it will also serve as yielding means for so holding the mold member 4 during the molding operation that it may yield to expansion of the metal and avoid necessity for 40 the use of other means for connecting the mold members either fixedly or yieldingly.

Referring now more specifically to the mold members 3 and 4, it will be observed (as indicated in Figures 5, 6 and 9) that 45 each of said mold members is provided with a chamber or jacket 20 to receive a heating media which may be conducted thereto from any convenient source of supply, by pipes indicated at 21.

In the embodiment of my invention shown in drawing, the mold member 3 is shaped to provide a female die 22 for a plow share and the mold member 4 is shaped to provide the male die 23,—these dies cooperating 55 when the mold members are brought together to provide a mold cavity, the diameter of which is so reduced at and near those portions in which the cutting edges of the share or point are cast as to facilitate chilling of 60 these parts. The respective mold members are made with channels 24 which cooperate to provide a pouring gate which is open at its upper end and extends under and communicates with the bottom of the mold cavity, preferably at two points, as indicated in 65

Figures 7 and 8. The respective mold members are also provided with vertical channels 25 which extend to and communicate with the mold cavity to provide for a riser from the casting. Each mold member 3 and 4 is made with a channel 26, wherein another riser may be formed on the body portion of the casting. In order that the share shall be provided with a bolt hole, the mold member 4 is provided with a hole 27 and a tube 28 extending across the chamber 20, to permit the insertion of a suitable core.

To facilitate the ejecting of the casting when the mold members are separated, the devices now to be described may be employed. A hole 29 (Fig. 5) is made in the mold member 4 in position to be in line with the base portion of the riser formed in the channel 26, and a tube 30 (having greater internal diameter than the diameter of the hole 29) passes through the chamber 20 in said mold member and communicates with said hole. A rod 31 passes through the tube 30 and is adapted also to pass through the hole 29 and to have frictional connection with the mold member 4. The rod 31 passes through an opening in a bracket 32 secured to the motor cylinder 11, said rod being provided with a head 33 to engage the bracket when moved in one direction or the cylinder 11 when moved in the other direction. When a share shall have been cast between the mold members and the mold members 4 is caused to move away from the mold member 3, the rod will move back with the mold member 4 until the head 33 on said rod strikes the cylinder 11. Further backward movement of the member 4, will cause the rod to engage the riser (formed in the channel 26) on the casting and free the latter, permitting it to drop through the opening 10 in the table. It should be explained at this point however, that when the mold member 4 moves away from the member 3, the latter will tilt forwardly and free the casting therefrom.

For casting a plow share or point having a chilled cutting edge portion, with the use of my improved apparatus, I may employ iron of any of the known grades, such as 115 foundry iron 1, 2, 3 or charcoal iron, or Bessemer iron, and in this iron I incorporate a chilling mixture comprising the following ingredients, in approximately the relative proportions stated,—viz, silicon 2.40 to 2.70 120 per cent, sulphur .06 to .15—per cent, phosphorus .120 to .250 per cent, and manganese .50 to .85 per cent. Or I might modify the chilling mixture as follows:—silicon 3.50 125 per cent, sulphur .06 to .15 per cent, phosphorus .120 to .250 per cent and manganese 1.00 per cent.

A plow share or point cast with the use of iron containing the chilling mixture above mentioned, in the mold cavity formed 130

by the permanent mold members hereinbefore described, will result in a substantial share or point 34 (Figure 10) having its cutting edge portions uniformly chilled, (the chilling occurring in that portion of the mold cavity having the reduced cross section), and extending an appreciable distance back of the cutting edge per se as at 35 and appreciable distances on both sides or faces 10 of the share or point as shown at 36, leaving a V-shaped unchilled portion 37 extending down into the chilled portion 35-36 to an extent limited by the analysis of the metal and the shape of the cutting edge portion 15 of the share or point and the temperature of the mold. A plow share or point is thus produced, which not only has a uniformly chilled edge, but which is strong and hard and capable of successfully withstanding 20 long usage.

If desired, in order to add strength to the share, nickel, chromium, titanium, vanadium or other such elements may be alloyed with the iron.

25 In operating the apparatus (assuming that the mold members are separated as shown in Figure 2), the operator will depress the free end of the lever 16 to shift the valve 15 and cause the motor to operate to 30 close the mold member. Either before or after thus closing the mold members and before pouring the metal, steam will be admitted into the chambers 20 of the mold members for heating said members to prevent the formation of "shot metal" and to 35 prolong the life of the mold members by eliminating quick expansion when the metal is poured. After the first casting shall have 40 been made, mixed water and steam will be admitted into the chambers 20 of the mold members to maintain a constant temperature.

45 After the mold members shall have been brought together as above described, the metal will be poured through the gate and will be conducted to the bottom of the mold cavity, gradually rising therein until the same shall become filled and the metal appears in or extends through the riser channels. The operator will then immediately 50 release the lever 16, thus causing reversal of the motor and the consequent separation of the mold members and the discharge or 55 ejecting of the cast share in the manner previously explained.

It will be observed that no latching means are employed for holding the mold members together, but that the air motor serves to properly hold the mold members together. 60 This air motor forms a yielding holding means so that should sudden expansion of the casting occur, whether such casting be a plow share or other object, such sudden expansion would be compensated for by the 65 yielding cushion afforded by the air motor.

Various changes might be made in the details of invention without departing from the spirit thereof or limiting its scope and hence I do not wish to restrict myself to the precise details herein set forth. 70

Having fully described my invention what I claim as new and desire to secure by Letters Patent, is:—

1. In a molding apparatus, the combination with a support, of a permanent mold member pivotally mounted on said support and adapted to tilt, a second permanent mold member mounted on said support to move toward and away from the pivoted mold member, means for moving said second mold member, means for controlling said moving means, and means carried by the said second mold member and operable automatically to free the casting when the mold members are separated. 85

2. In a molding apparatus, the combination with a support, of two permanent mold members mounted thereon and one movable relatively to the other, means for moving the movable mold member, means for controlling moving means, a rod passing through the movable member and having frictional connection therewith so as to be movable with and also independently of the movement of said movable mold member, and stop means for controlling the movements of said rod, whereby said rod will operate automatically to free the casting when the mold members are separated and be prevented from entering the mold cavity 100 when the mold members are closed against each other. 95

3. In a molding apparatus, the combination with a support, of two permanent mold members thereon and one movable relatively to the other, of a motor connected with the movable mold member, a rod passing through and having frictional connection with said movable mold member, a head on said rod, a bracket secured to the motor and through which said rod passes with the head thereof between a part of the bracket and said motor, and means for controlling the operation of the motor. 105

4. In molding apparatus, the combination with a support, of two permanent mold members mounted on said support, one of said mold members being movable relatively to the other, a fluid pressure motor connected with the movable mold member, a valve for controlling the supply of fluid to respective ends of said motor, an operating lever, and connections between said lever and said valve and operating normally to hold the valve in position to supply fluid to cause the motor to hold one of said mold members separated from the other and to move the valve to such position to effect separation of the mold members. 125

5. Molding apparatus comprising two 130

permanent mold members, each having a chamber, means whereby heating fluid may be introduced into said chamber, said mold members cooperating to form a mold cavity having a reduced cross section near an edge portion thereof, and means for effecting movement of one of said mold members relatively to the other.

6. The herein described method of making a plow share or point having a chilled cutting edge portion, consisting in casting said share or point between permanent mold members forming a mold cavity having reduced cross section where said cutting edge portions are cast, with the use of iron containing silicon, sulphur, phosphorus and manganese in the relative proportions substantially as specified.

7. The herein described method of making a plow share or point having a chilled cutting edge portion, consisting in pouring into a suitably shaped cavity of a jacketed or chambered metal mold, a chilling iron

alloy, and discharging into the jacketed or chambered portions of the mold, mixed water and steam.

8. The herein described method of making a plow-share or point having chilled cutting edge portion, consisting in discharging steam into the chambers or jacket portions of two metal mold members, bringing the mold members together, pouring a chilling iron alloy into the mold cavity, separating said mold members and discharging the casting, and subsequently discharging combined water and steam into said chamber or jacket portions and retaining the same therein during subsequent molding operations.

In testimony whereof, I have signed this specification in the presence of two subscribing witnesses.

EDMUND JAMES LOWRY.
